UNITED STATES PATENT OFFICE.

SIDNEY C. BURT, OF CHICAGO, ILLINOIS.

VENTILATOR.

Application filed March 29, 1926. Serial No. 98,209.

These improvements relate broadly to ventilators and are designed more particularly for use on passenger railway cars and closed automobiles such as coupes, sedans, 5 limousines, and the like, to ventilate a passenger compartment thereof.

The prime object of the present improvements is to introduce the desired amount of ventilating air without at the same time introducing an objectionable amount of dust and dirt from the road. It is an object to provide a ventilating device of such character and which may be positioned in an out-of-the-way or normally nonvisible part of 10 the car or automobile to avoid the objection of an unsightly appearance. Another object is to provide a form of ventilator according to which air may be caused to enter the compartment or to be drawn out 15 therefrom through the ventilator, the latter function being a feature of advantage in removing smoke-laden, or foul air. It is also an object to provide a ventilator which may be made and installed cheaply and which, 20 when applied in the preferred location, namely below the floor of the vehicle and not readily to be observed, may be of such a considerable size as to provide the desired ventilation where the hollow interior to be 25 supplied is of considerable volume. For instance, the large hollow interior of a motor bus may be ventilated by a single unit according to the present improvements embodied in a size suitable for the purpose, 30 which size is rendered passable and without objection through the location of the device where it is not seen from the street.

In the drawings Figure 1 is a fragmentary side view of a motor car of an enclosed 40 type having parts broken away to show the present improvements installed in a preferred general location; Fig. 2 is a medial vertical longitudinal section through the form of ventilator shown in Fig. 1, on an enlarged scale as viewed in the opposite direction; and Fig. 3 is a sectional and end view on the broken line 3-3 of Fig. 2.

My improved ventilator is formed almost entirely of thin sheet metal, for instance 45 galvanized iron. Beginning at the right-hand end of Fig. 2, namely at the air intake, the intake member comprises first a

cylindrical tube 9 open at the free end to provide a substantially large intake opening 10, the ring merging into a conically 55 tapering section 11 which terminates in a short tubular nozzle 12 shown as being slightly flaring toward its free and open discharge end 13. This somewhat funnel-like structure comprising the parts 9, 11 and 12 is supported at the normally front end by a circular plate 14 open centrally to receive the air-intake member, the ring 14 and the parts 9-11 being rigidly secured together, as by soldering or any other approved means.

The air-intake member parts 11-12 extend into the hollow interior of a substantially large hollow body comprising first a conically-tapered part 16 which at its top 70 portion merges into a vertical wall 17 spaced from the front vertical wall 14 to form an air discharge channel 18 of rectangular shape leading through the floor-board 19 and opening into the hollow interior of the 75 car.

Extending from the inwardly-tapering outer member 16 is the outwardly-flaring part 20 of the housing or body member, and extending rearward from the member 20 is 80 a cylindrical part 21.

The air-intake member 9-11-12 is shown as being further supported by three rods 23 secured to it and to the outer shell or body member 20. The outer body members and parts are all rigid with each other and the air-intake member is rigidly held in spaced relation as shown so as to occupy 85 a centrally-directed or substantially axial position with respect to the main body member.

A butterfly valve 24 at the intake opening may be operated in any approved way. I have shown simple means for the purpose comprising a lever 25 connected to a push-and-pull rod 26 extending through the floor-board and having a knob 27. A similar butterfly valve 30 at the free end of the body member 21 may similarly be opened and closed by means of a lever 31 and a push-and-pull rod 32 having the knob 33. The device as a whole may be held to the floor-board by means of several cleats 35 (Figs. 1 and 3).

The operation of the device to introduce air into the passenger compartment is as follows: The valve 24 at the intake is opened and the valve 30 is closed. The forward motion of the car developing air pressure at the intake causes air to enter the opening 9. For a passenger automobile of the coupe or sedan type a diameter of say four inches for the opening 9 will be sufficient. The velocity of the air within the cylindrical part 9 is increased somewhat by the narrowing wall 11. Such increase of velocity has a functional effect.

The air entering the device contains dust and dirt from the road which it is desired to separate out. Such separation occurs first through the fact that the air discharged from the opening at 13 enters a relatively large compartment and the rate of movement of the air is reduced. The solid particles, however, having greater momentum than the air particles, continue to move ahead and strike the closed valve 30 or begin to settle upon the lower inner surfaces of the body member. A further separation then takes place through the change of direction in the air current. As shown by the arrows indicating the air flow, this flow is first toward the obstruction or wall 30. This obstruction causes the current to turn and move first radially outward and then back upon itself or forward in an annular column surrounding the middle rearwardly-directed column. The dust and dirt particles, being heavier than the air particles, tend to continue in a straight line, and to pass out of the air current and strike a wall of the device, adhering thereto. Wherever in the air movement such a change of direction occurs, whether medially between the end of the nozzle 12 and the valve 30 or close to the valve, this separation of the solid matter takes place, but it occurs to the greatest extent near the plate 30 where the greatest change in the direction of the air current is had.

Passing forward, the air enters between the tubular nozzle 12 and the flaring outer wall 20 and comes to a more restricted opening 35 where its velocity is again increased, and it thence issues into a substantially large ring-like compartment 36. The tendency of the dust particles passing through the throat at 35 is to continue forward and strike the front wall 14, for the air current here changes its direction from say horizontal to vertical so as to issue through the discharge opening 18.

What I consider to be the more important functional principles involved in the operation of the device are the temporary slowing down of the air movement at one or more places in the course of travel whereby dust particles may more readily pass out of the air current and into contact with a wall of the structure, the changing of the direction

of the air flow abruptly at preferably several places in the course of travel, the joint action of a slowed current and such change of direction, and the provision of surfaces adapted to be contacted by and to hold dust particles leaving the current at any place.

It will be noted that the most abrupt change in the direction of the air flow occurs adjacent to the closure 30 in the body member and at a time when the air stream contains the greatest amount of dust, that a smaller change occurs at the throat 35, and that another abrupt change in the direction occurs when the current strikes the end wall 14. The current flowing toward the throat 35 meets a conical wall formation in the plate 11 and the outer wall 20, which also receive deposits of dust and dirt, and the slanting formation of the wall 20 has the further function of forming a pocket or relatively low portion at the bottom defined by the dotted line 37 in Fig. 2 adapted to hold a quantity of collected dust. Ordinarily, however, the dust does not collect up to the line 37, but fills the corner portions at the valve 30, although a goodly amount collects on the lower inner surface of the body. It is contemplated that the device will be cleaned from time to time to prevent undue filling thereof.

At 40 (Figs. 2 and 3) I have provided a small swinging closure adapted to cover the opening 41 through which a cleaning instrument may be applied to remove collected dirt from the lower portion of the chamber 36. This opening also serves to drain that compartment when the valve 30 is opened and the device as a whole is cleaned by directing a water hose into it. By opening the valve 30 to cause a stream of air to pass directly through the body member the greater bulk of the dust in the main portion thereof is carried away.

By dotted lines I have shown an air heater 42, which may be of the type using some of the engine exhaust and around the coils of which the air from the passageway 18 passes.

When it is desired to ventilate by withdrawing air from the passenger compartment of the vehicle through the device it is only necessary to open the valve 30, as by pulling up the knob 33. A stream of air is therefore caused to pass through both the inner and outer tubular members tending to entrain air from about the nozzle 12, and tending to produce a partial vacuum which draws air downward through the passageway 18. This feature is of importance in instances where the compartment contains impure air which it is desired to remove, as for instance in crowded busses or in street or railway cars. With means for withdrawing air the desired circulation is had through the fact that there is always a considerable

- seepage of air through various openings in the body of a car, around windows and doors, etc. Very little air enters at these casual openings or crevices under ordinary 5 conditions on account of the cushioning effect of the body of air within the hollow interior, but outer air enters freely at such openings when a sufficient withdrawal of inner air takes place.
- 10 Another particular advantage of this reversal of the ventilation stream is in such instances as where the automobile may be forced to follow closely another automobile discharging noxious gases of combustion 15 close to the ground and which would find objectionable entrance into the passenger compartment if the device were operated in the direct way. Such instances are of more rare occurrence, but are thus readily provided for, as by a mere lifting up of the knob 33. As mentioned, too, the main dust-collecting portion of the device may be cleaned of accumulated dust by reversing the 20 operation from time to time.
- 25 By operating the knob 27 the supply of intake air is controlled. In cold weather the ventilation air called for is usually less than in warm weather, unless the incoming air is suitably warmed, as by the heater 42. Furthermore, since the air inflow will depend upon the rate of travel, the valve 24 may be operated to reduce the intake when the machine is traveling at a relatively high rate 25 through long stretches, as in touring.
- 30 Apart from the dust-separating feature the present improvements constitute a simple, relatively cheap and highly advantageous form of ventilation useful on all such vehicles.
- 35 I contemplate as being included in the improvements thus specifically illustrated and described all such changes, variations, departures and modifications therefrom as fall within the scope of the appended claims.
- 40 I claim:
1. In a dust-separating ventilator of the character described, the combination of a hollow body having an air deflector therein, hollow air intake means having an intake 45 opening and a discharge opening for introducing a stream of air into the body so as to be directed against said deflector, the deflector being adapted and arranged to cause the air current to spread radially outward, 50 the hollow body being formed to direct such spread current to flow back and around the intake air stream, with air discharge means 55 opening into the body at a materially great distance from said deflector to provide for a materially long travel of dust-laden air with a slowed movement from the deflector to the discharge means.
  2. The combination of claim 1 hereof in which said deflector is a valve operable to 60 open the end of said hollow body.
  3. The combination of claim 1 hereof in which there is also a valve for regulating the flow of air through the intake means.
  4. The combination of claim 1 hereof in which there is a constricted passageway intermediate the discharge opening and the deflector, and in which there is an enlarged body formation adjacent to said constricted passageway providing an enlarged air space of the hollow interior into which the air 75 passes from said constricted passageway, the discharge means opening into said enlarged formation.
  5. In a ventilator of the character described, the combination of an outer tubular member having a closure at one end, an inner tubular member extending into the outer member and directed toward said closure, the inner tubular member being open at both ends and being of a smaller diameter where it discharges into the outer member, the outer member being closed where the inner member enters the hollow interior except for the opening thereinto provided by the inner member, there being a discharge opening for air in the outer member adjacent to the end thereof occupied by the inner member and at a materially great distance from said closure to provide for a materially long travel of dust-laden air from 80 the deflector to the discharge opening, the arrangement being such that air passing into the outer member through the inner member is deflected in a general direction back toward the entrance opening of the inner member and thence through said discharge opening.
  6. The combination of claim 5 hereof in which said closure is a valve operable to open the end of said outer tubular member.
  7. The combination of claim 5 hereof in which there is also a valve for regulating the flow of air through the inner tubular member.
  8. In a ventilator adapted to be positioned on a vehicle to gather air for the ventilation thereof, the combination of a hollow body having means for introducing a column of air thereinto through the air pressure generated by the motion of the vehicle, means having a discharge opening for leading air from said body to the hollow interior of the vehicle, and means within said body for deflecting the air column to form a reversely-flowing envelope of air 115 around the intake air column to separate solid particles from the air before it reaches the discharge opening, the discharge opening being at a materially great distance from the deflecting means, for the purposes specified.
  9. In a ventilator adapted to be positioned on a vehicle to gather air for the ventilation thereof, the combination of a hollow body having means for introducing air thereinto 120 around the intake air column to separate solid particles from the air before it reaches the discharge opening, the discharge opening being at a materially great distance from the deflecting means, for the purposes specified.

through the air pressure generated by the motion of the vehicle, said body having a discharge opening for leading air from said body to the hollow interior of the vehicle, and deflecting means within said body for changing the direction of the air current abruptly to separate solid particles from the air before it reaches the discharge opening, the discharge opening being at a materially great distance from the deflecting means to provide a relatively long travel of air from the deflecting means to the discharge opening, for the purposes specified. 10

SIDNEY C. BURT.
